COOLING SYSTEM FOR X-RAY APPARATUS
Cormack E. Boucher, Seattle, Wash., assignor to
Ind-X Corporation, Seattle, Wash., a corporation
of Washington

Filed Feb. 26, 1962, Ser. No. 175,602

6 Claims. (Cl. 250—89)

The present invention relates to X-ray apparatus and more particularly to an arrangement for cooling an X-ray tube.

As is well known, copious amounts of heat are generated in the anode of an X-ray tube during its operation and the ability to remove such heat is frequently a limiting factor in the operation of the tube. Cooling systems of circulating fluid are frequently utilized but such systems as heretofore provided are frequently troubled with mechanical breakdown of the pump.

It is, therefore, an object of the present invention to provide a cooling arrangement for an X-ray tube which is not subject to mechanical breakdown.

More particularly, it is an object of the present invention to provide a circulating fluid cooling system for an X-ray tube utilizing an ion drag pump to effect circulation of fluid.

Still another object of the present invention is to provide a new and improved X-ray apparatus including a fluid circulating system for removing heat from the X-ray tube and in which the high voltage transformer supplying accelerating potential to the electrodes of the X-ray tube is utilized to supply accelerating potential to an ion drag pump effecting circulation of fluid in such system.

Another object of the invention is to provide an X-ray apparatus and fluid circulating system of the type described above wherein the X-ray tube is utilized as a rectifier to supply D.C. potential to the ion drag pump.

Other objects and advantages of the invention will become more apparent hereinafter.

For a more detailed description of the invention reference is made to the following specification and the accompanying drawings, wherein:

FIG. 1 is a sectional elevation of X-ray apparatus made in accordance with the invention;

FIG. 2 is an enlarged sectional view taken along line 2—2 of FIG. 1.

FIG. 3 is a sectional view taken along line 3—3 of FIG. 2;

FIG. 4 is a schematic view of an electrical circuit for the apparatus of the invention; and

FIG. 5 is a schematic view of a preferred embodiment of the circuit of the invention.

Referring now to the drawings, the invention is illustrated in connection with X-ray apparatus including a sealed, tubular housing 10 including a generally cylindrical portion 12 and removable end domes 14, 16. The housing 10 may be of magnesium or other suitable lightweight material.

Mounted within the housing 10 is a transformer having a rectangular core 19 and windings or coils 20, 21. Suitable leads 22, see FIGS. 4 and 5, are provided to connect the transformer to an external source of A.C. power. Suitably supported between the windings 20, 21 is an X-ray generator or tube 24 comprising a suitable sealed envelope 26 in which are mounted an anode 28

2

and a cathode 30. The anode 28 is connected by a lead 32 to the secondary of the transformer winding 20 and the cathode 30 to the secondary of the transformer winding 21 by a lead 34 whereby accelerating potential may be applied between the cathode and the anode. A further lead 36 is connected to a tap on the secondary to provide current for heating the filament of the cathode.

The cooling system of the invention includes a heat exchanger 40 to remove heat from the anode which exchanger may be of any known type and may comprise, for example, a conduit 41 of copper or other suitable material arranged in close association or contact with the anode stem 42 which extends exteriorly of the envelope 26. An insulating shield 46 may be positioned between the heat exchanger and the housing 10. Suitably supported upon the end dome 16 is a coil type radiator 50 connected to the heat exchanger 40 by conduits 52, 54 of Teflon or other electrically non-conductive material which pass through the dome 16 through suitable seals 55. The radiator 50 is protected by a perforated shell 56 suitably secured to the end of the tank 10. A fan 58 preferably is provided to cause circulation of air through the shell and past the radiator 50.

In accordance with the invention circulation from the heat exchanger 40 to the radiator 50 and return is attained by means of an ion drag pump 60 installed in the conduit line 54. The pump 60 comprises a cylindrical casing 62 of a suitable insulating material and an ion emitter 64 and a collector 66 mounted in spaced relation. The ion emitter 64 comprises an electrically conductive plate perforated to permit fluid flow therethrough and has mounted on one surface thereof a plurality of needles 68 which define corona discharge points. The collector 66 is spaced downstream from the emitter 64 in the desired direction of fluid flow, and has a plurality of openings 70 preferably axially aligned one with each of the corona discharge points 68. The coolant system is filled with a fluid of high dielectric strength and preferably with a liquid dielectric such as transformer oil, kerosene or a liquid fluoro chemical.

As will be understood the application of a high negative potential to the emitter 64 will cause corona discharge to occur at the points 68 effecting a generation of ions which will be attracted toward the positive collector 66, a large proportion of the ions passing through the openings 70 because of their high velocity and falling back to the collector 66 on the far side thereof. In their movement the ions will induce a flow of coolant fluid in the direction from the emitter 64 to the collector 66 and will also induce flow of the fluid through the openings 70 in the collector plate to initiate circulation of all of the fluid in the system in the direction of movement of the ions so that the fluid will flow through the heat exchanger 40 to the radiator 50 and thence back to the ion drag pump 60.

It will be understood that the ion pump electrodes 64, 66 may be supplied with A.C. potential directly from the transformers 20, 21 but the application of D.C. potential results in greater pumping efficiency.

Referring now to FIGURE 4, in accordance with one embodiment of the invention the X-ray tube 24 is utilized as a halfwave rectifier in a circuit to supply pulsating direct current to the ion drag pump. In accordance with this arrangement a voltage dropping resistor 71 is placed

in the line 32 between the anode 28 and the transformer 20.

The leads 72, 74 connect the collector and emitter, respectively, to the opposite ends of the resistor 71 so that a positive potential is supplied to the collector 66 and a negative potential (with respect to the collector) to the emitter 64.

A preferred embodiment of the invention is shown in FIG. 5 wherein a bridge rectifier 80 supplied from a tap 82 on the transformer 20 is utilized to supply a steady D.C. potential to the ion pump electrodes 64, 66. The steady potential supplied by such a rectifier results in an increase in the efficiency of the ion pump and thus better circulation of the fluid.

An X-ray tube cooling system constructed in accordance with the invention has a number of advantages. The ion pump 60 is of course exceedingly simple in construction, is silent in its operation and having no moving parts is not subject to mechanical breakdown. It can moreover, if desired, be placed at elevated voltages above ground and be excited by a portion of such voltage. Moreover, the power consumption of the ion pump is for all practical purposes negligible.

Having illustrated and described certain preferred embodiments of the present invention, it should be apparent to those skilled in the art that the invention permits of modification in arrangement and detail. I claim as my invention all such modifications as come within the true spirit and scope of the appended claims.

I claim:

1. An X-ray apparatus comprising an X-ray generator comprising a cathode and an anode, a high voltage transformer for supplying accelerating potential to said generator, a cooling system for removing heat from said anode comprising a fluid circulatory system including a radiator, a heat exchanger operatively associated with said anode to extract heat from the latter, an ion drag pump comprising an emitter means and a collector means, conduit means connecting said radiator, said heat exchanger and said ion drag pump in a closed series circuit, a dielectric fluid filling said system, and means supplied from the secondary of said high voltage transformer for supplying a high D.C. voltage to said emitter means and a collector means.
2. An X-ray apparatus comprising a sealed housing, an X-ray tube in said housing, said X-ray tube comprising a sealed envelope and a cathode and an anode, a high voltage transformer in said housing for supplying accelerating potential to said tube, said anode comprising a stem extending outwardly of said envelope, a cooling system for removing heat from said anode stem and transmitting the same exteriorly of said housing comprising a fluid circulatory system including, a radiator positioned exteriorly of said housing, a heat exchanger operatively associated with said anode stem to extract heat from the latter, an ion drag pump comprising an emitter means and a collector means, conduit means connecting said radiator, said heat exchanger and said ion drag pump in a closed series circuit, said conduit means extending through the housing wall and being sealed therein, a fluid of high dielectric strength filling said system, an electrical resistor in series with said anode and said transformer, and means connecting said emitter means and said collector means across said resistor.

3. An X-ray apparatus comprising an X-ray generator comprising a cathode and an anode,

a high voltage transformer in said housing for supplying accelerating potential to said generator, a cooling system for removing heat from said anode comprising a fluid circulatory system including a radiator, a heat exchanger operatively associated with said anode to extract heat from the latter, an ion drag pump comprising an emitter means and a collector means, and conduit means connecting said radiator, said heat exchanger and said ion drag pump in a closed series circuit, a dielectric fluid filling said system, and means supplied from the secondary of said high voltage transformer for supplying a high voltage to said emitter means and collector means.

4. An X-ray apparatus comprising a sealed housing, an X-ray tube in said housing, said tube comprising a sealed envelope and a cathode and an anode, said anode comprising a stem extending outwardly of said envelope, a cooling system for removing heat from said anode stem and transmitting the same exteriorly of said housing comprising a fluid circulatory system including a radiator positioned exteriorly of said housing, a heat exchanger operatively associated with said anode stem to extract heat from the latter, an ion drag pump comprising an emitter means and a collector means, and conduit means connecting said radiator, said heat exchanger and said ion drag pump in a closed series circuit, said conduit means extending through the housing wall and being sealed therein, a fluid of high dielectric strength filling said system, and means in said housing for supplying high voltage to said emitter means and collector means and to said cathode and anode.

5. An X-ray apparatus comprising a sealed housing, an X-ray tube in said housing, said X-ray tube comprising a sealed envelope and a cathode and an anode, a high voltage transformer in said housing for supplying accelerating potential to said tube, said anode comprising a stem extending outwardly of said envelope, a cooling system for removing heat from said anode stem and transmitting the same exteriorly of said housing comprising a fluid circulatory system including a radiator positioned exteriorly of said housing, a heat exchanger operatively associated with said anode stem to extract heat from the latter, an ion drag pump comprising an emitter means and a collector means, conduit means connecting said radiator, said heat exchanger and said ion drag pump in a closed series circuit, said conduit means extending through the housing wall and being sealed therein, and a fluid of high dielectric strength filling said system, and means supplied from the secondary of said high voltage transformer for supplying a high D.C. voltage to said emitter means and collector means.

6. An X-ray apparatus comprising an X-ray tube, said tube comprising a sealed envelope and a cathode and an anode, a high voltage transformer supplying accelerating potential to said tube, said anode comprising a stem extending outwardly of said envelope,

a cooling system for removing heat from said anode stem comprising a fluid circulatory system including a radiator,
 a heat exchanger operatively associated with said anode stem to extract heat from the latter,
 an ion drag pump comprising an emitter means and a collector means,
 conduit means connecting said radiator, said heat exchanger and said ion drag pump in a closed series circuit,
 a fluid of high dielectric strength filling said system, and means supplied from the secondary of said high

voltage transformer for supplying a high D.C. voltage to said emitter means and collector means.
